INTERNAL INSULATION STRUCTURE FOR USE WITH LIQUEFIED PETROLEUM PRODUCTS

Frank A. Clauson, Roslyn Heights, N.Y., assignor to Texaco Inc., a corporation of Delaware

Filed Dec. 19, 1957, Ser. No. 703,916

2 Claims. (Cl. 220—15)

This invention relates generally to insulation for low temperature refrigerated products and specifically to internal insulation construction for the storage, maintenance and transportation of normally gaseous hydrocarbons in liquid condition.

In domestic petroleum production, utilization of large quantities of petroleum gases is accomplished at nearby facilities, while the transportation of these gases from producing fields to relatively distant points is largely by transcontinental pipelines and to some extent by cargo containers.

Containers built to withstand very high pressures are used in shipment of liquefied petroleum gases for considerable distances. However, the cost of manufacture of the heavy containers, due to the amount of material required, as well as the expense of transportation, restricts the shipment to closeby establishments. At the same time, the size of such containers is limited because of the maximum allowable metal wall thickness permitted without stress relief.

While it is known to transport and store low temperature liquefied gases, such as nitrogen and oxygen, in Dewar type containers consisting of spaced inner and outer receptacles, the problems involved in the construction of such type containers for the shipment of the large quantities of liquefied petroleum gases required to justify their economical transportation prevents their widespread use.

Other means for the transportation of liquefied petroleum gases at extremely low temperatures and at substantially atmospheric pressure have not proven successful in commercial operation, including the use of insulated tanks mounted on barges or in vessels, the tanks being considerably larger than the pressure containers and employing balsa wood for insulation. Because of the amount of such insulation required, both interior and exterior, the usable dimensions and hence the capacities of the tanks are reduced considerably. In addition, there is the danger of low temperature embrittlement of carbon steel tank walls which might occur should the insulation drop off and expose the walls to liquefied petroleum gas. In the absence of the use of high cost alloy steels for constructing the tanks, the shipment of liquefied petroleum gases is restricted by safety standards to the relatively heavier petroleum gases which have the higher boiling points.

The storage and transportation of liquefied petroleum gases in low pressure tanks offers considerable promise if an adequate means of insulating the tank walls were developed. Although there are available satisfactory means of external insulation for such stationary tanks, obviously this solution is not practical on the exterior of a tanker. Even on stationary tanks, exterior insulation presents problems of condensation and corrosion beneath the insulation. In extremely low temperature situations, exterior insulation is not desirable because the supporting metal structure must be made of extremely expensive alloys that are not subject to embrittlement and low impact strength at low temperatures.

2

Internal insulation avoids both the corrosion and embrittlement problems but difficulty arises in the maintenance of the structural strength of the insulating material as a result of rapid ebullition within the voids of the insulating material and in the avoidance of sloughing off of the insulation from the wall of the container.

Accordingly, it is an object of the present invention to provide a new and improved structure for economic maintenance of low temperature liquefied gases in light weight, low pressure tanks.

Another object of the invention is to provide a novel construction for the storage and/or shipment of low temperature materials, the cost of which is negligible as compared with other means.

Still another object of the invention is to provide a simple internal insulation for the shipment and/or storage of liquefied petroleum gases in which the dangers of construction failure are virtually eliminated.

And another object of the invention is to provide a novel internal insulation in either a static or mobile apparatus for the maintenance of normally gaseous hydrocarbons in liquid form.

These and other objects, advantages and features of the present invention will become apparent from the following description of the invention and by reference to the accompanying drawings wherein:

Fig. 1 is a partial diagrammatic view of a wall of a container for holding liquefied petroleum gases; and

Fig. 2 is a cross-section taken along the line 2—2 in Fig. 1, disclosing the internal insulation construction in greater detail.

In accordance with the illustrated embodiment of my invention, I employ vaporized gas from the cargo of liquefied petroleum gas as a barrier between the liquid and the wall of the container to provide necessary insulation.

Referring to the figures in the drawing, there is disclosed an outer wall W of a container, holding liquefied petroleum gas, (the showing of which is omitted for purposes of clarity) and a series of overlapping thin metallic shields S, which are shown attached, e.g., by welding, at their top and bottom edges respectively to the outer wall and the immediately adjacent overlapped shield, as at 10 and 11. The attachment along the top edge is complete hermetically and forms a total seal, while the attachment along the bottom edge may be interrupted, as by spot welding of the edge, or, when complete, by the provision of notches 12 therealong or adjacent the bottom edge. The side edges, i.e., the ends of individual pieces of shields, may be fastened to the outer wall, and when the construction is used in a tanker could be welded to the longitudinal ribs of the tanker, or to the contiguous edges of the adjacent shields to form a continuous strip around the interior of the container. The method of attachment of the side edges is considered optional and when fastened to the outer wall, the quantity of heat transferred through the thin metal shields is very small. The shields S are spaced from the outer wall at a distance A, Fig. 2, which may vary to 12 inches, while the distance B, Fig. 2,

between the fastening of the top and bottom edges of the shield may vary from 2 to 10 feet, these dimensions varying with the insulation requirement and the thickness of shield available economically, as well as the material used, e.g., alloy steel, sheet iron or foil. Since the shield thickness is small and stresses thereon so low, the problem of low temperature embrittlement is avoided with the shield materials. Although a pronounced angularity is disclosed along the line of fastening of the lower edges to the overlapped shield, such is not required always.

In addition, the insulation spaces or chambers C defined between the outer wall and the overlapping shields may be filled with insulating material M, (shown in Fig. 70)

2) either carbonaceous or siliceous, such as foam glass, rock wool and the like, to further impede any formation of convection currents in the spaces, virtually eliminated by the use of multiple vapor traps along the vertical side walls of the containers.

The operation of the structure will now be described. As the liquefied petroleum gas is delivered to the storage or transport container having either an insulated bottom or a bottom of high strength alloy, liquid gas enters the insulation spaces at the lower edges of the shields through the perforations or openings 12 and vaporizes therein. The vaporized gas provides a gaseous barrier between the thin metal shield in contact with liquefied petroleum gas and the outer wall and also serves as a vapor seal to prevent any further entrance of liquefied petroleum gas into the spaces.

Thus, a vapor barrier is created between the liquid and the outer wall to provide the necessary insulation. Referring to Fig. 2, the liquefied petroleum gas which has penetrated into the insulation space or vapor trap C is indicated at L and the vaporized gas at V. This differentiates over the prior art practice wherein it is required that the insulation be soaked with liquid while the present invention intends that after the initial leakage, the vapor would be trapped in the space or chamber and would exclude further penetration of liquefied petroleum gas.

Since the insulation which would be maintained within the insulating chambers is always included in the vapor space, it will not be subjected to deterioration by ebullition. Should the insulating material deteriorate, serious damage will not occur to the container wall since the metallic shield provides for structural support of the insulating material and the vapor barrier prevents contact of the liquefied petroleum gas with the container wall.

The height (i.e., the width) of the metallic shield can be varied if desired. The lower the height of the shield, the smaller the static head pressure differential between the vapor space and the liquid so that a thinner metallic shield can be used. It should be noted that in any case the shields are subjected only to this small differential static head and any pressure in the container is transmitted to and supported by the outside wall.

Thus, there has been disclosed a structure wherein the cost of low temperature internal insulation is negligible as compared with other similar insulation. The invention can be used as readily for permanent shore installations for storage purposes as well as for the transportation of liquefied petroleum gases as well as for other low temperature liquefied products, e.g. ammonia, in ocean-going tankers or in railroad tank cars and can be used either with circular and cylindrical wall sections as well as with the straight wall as shown herein, and in pressurized containers.

Obviously, many modifications and variations of the invention as hereinbefore set forth may be made without departing from the spirit and scope thereof, and therefore, only such limitations should be imposed as are indicated in the appended claims.

I claim:

1. In combination with the side wall of a light weight container for holding at low temperature and at low pressure a liquefied product normally gaseous at ambient temperature, an internal insulation structure comprising a plurality of panel members each having top and bottom edges and being fastened hermetically along each of their top edges to the internal surface of said side wall in a substantially horizontal plane, each of said panel members having a continuous top edge portion extending from said top edge inwardly and downwardly with respect to said side wall and ending at a vertical portion thereof extending downwardly parallel to and spaced from said side wall, said panel members being positioned in vertical overlapping relationship to each other with the bottom edge of one course of said panel members being fastened at spaced intervals to the subjacent course of said panel members along the juncture of the inwardly extending continuous top edge portion with the vertical portion thereby to define a series of vertically aligned peripheral chambers to serve as individual vapor traps for vaporized gas from said liquefied product entering said chambers along the bottom edges thereof, the cross section of each of said chambers being a parallelogram having acute and obtuse angles, the angle at the juncture of the top edge of each panel member with said side wall being of such magnitude that the vaporization of said liquefied product in each of said chambers provides a vapor barrier between said liquefied product and said side wall and a vapor seal to prevent further ingress of said liquefied product thereto, said bottom edges of said panel members having a series of notches therein, the top edge of said notches in each panel member defining a substantially horizontal plane which is substantially below the plane of the top fastened edges of the subjacent course of said panel members.
2. In the combination as defined in claim 1, said peripheral chambers defined by said side wall and said panel members and comprising said vapor traps being filled with a filamentary insulating medium.
